UNITED STATES PATENT OFFICE.

FOSTER RITCHIE, OF ACTON, ENGLAND.

TELEWRITER APPARATUS.

1,123,381.

Specification of Letters Patent.

Patented Jan. 5, 1915.

Application filed December 10, 1910. Serial No. 596,611.

To all whom it may concern:

Be it known that I, FOSTER RITCHIE, a subject of the King of Great Britain, residing at 36 King Edwards Gardens, Acton, in the county of Middlesex, England, electrical engineer, have invented certain new and useful Improvements in Telewriter Apparatus, of which the following is a specification.

10 This invention relates to telewriter or telautograph apparatus and in particular to the paper feeding devices of such apparatus.

The primary object of the present invention is to provide a more powerful and silent 15 running paper-shifting apparatus than has been possible hitherto with the usual single direct pull electromagnet type of apparatus, and with this object the paper-shifter is actuated by means of an electric motor which 20 is connected with the paper gripping apparatus through a crank or equivalent gear, thereby obviating the necessity of providing any stop abutment for determining the feed of the paper the use of which gives rise to 25 noise in working the apparatus, while at the same time insuring an absolutely definite stroke of the paper feeder.

The improved apparatus possesses the further advantages of being less sluggish 30 in action than existing devices, the moving and magnetic parts of the motor having but little inertia as compared with the equivalent parts of a single direct pull magnet, so that the moving parts of the motor attain their normal speed substantially instantaneously. Moreover, the currents required 35 for the working of the motor are much smaller and therefore more easily dealt with than in known apparatus in which the currents are so heavy that if, for example, the 40 paper became deranged so as to arrest the movement of the actuating magnet, there was a serious liability of the windings being burned up unless an automatic cut-out, 45 for example an electric thermostatic cut-out, were provided. In the improved apparatus the motor is sufficiently powerful to tear the paper should the feed of the latter be improperly arrested.

50 According to the present invention therefore the paper is gripped and fed by a mechanism which is actuated by an electric motor, this motor being connected through suitable gear and a crank pin and connecting rod or equivalent linkage with an arm

on the shaft which carries the paper grippers. The motor which is fed from a suitable source of direct current, actuates not only the paper grippers but also, synchronously therewith, a switch which is associated with a relay operated by the writing currents. The connection between the gripping mechanism and the driving motor is such that at what may be regarded as the starting position the first movement of the 60 gripping device due to the rotation of the crank causes the grippers to close on the paper and hold it fast against coöperating surfaces. The continued rotation of the crank shifts the gripping device and with 65 it the paper at a speed which, at first slow, rapidly accelerates and again slows down. On the cessation of the momentary writing current the relay is deenergized and its armature is retracted by its spring against 70 the idle stop. The apparatus is so designed, however, that before this can occur the switch has been shifted so as to establish a circuit to the motor through the idle stop of 75 the relay, and consequently the motor will 80 continue to work. After half a turn of the crank actuating the gripper, the movement of the gripping device is reversed, the first part of the reverse movement causing the release of the paper and the remainder of the 85 movement returning the device to such a position that the circuit to the motor is again established through the working stop of the relay when the latter is again energized by a writing current.

90 The preferred construction of motor for operating the paper shifting mechanism has a four-pole soft iron armature, the field magnet having six pole pieces connected in pairs the energizing coils of which are connected with the bars of a 12-bar commutator which is stationary, while the brush or brushes coöperating with the commutator are mounted on the armature shaft and revolve therewith, the arrangement being such 95 that the armature gets twelve impulses each 100 revolution, and being of small weight it starts up quickly and has no over-run.

105 The invention is illustrated in the accompanying drawings, Figure 1 is a plan view looking at the underside. Fig. 2 is a front elevation, and Fig. 3 an end elevation of the improved apparatus, Figs. 4 and 5 being transverse sections showing the gripping device in two positions, one (Fig. 4) 110

being the position in which the paper is gripped and the paper shifter is just beginning its forward stroke, and the other (Fig. 5) in which the paper is released and the shifter is half-way on its return or idle stroke; Fig. 6 is a diagrammatic representation of the relay and switch connections; and Fig. 7 is a diagram of the motor connections.

10 The gripping device is carried by a pair of arms *a* extending upwardly from the rock shaft *b* upon which is mounted switch arm *c*. Extending between and journaled in the ends of the arms *a* is a shaft *d* upon which are fixed the grippers *d'*. These grippers coöperate with eccentric pins *e* adjustably secured in the ends of the arms *a* in proximity to the grippers *d'*. By rotation of these eccentric pins it may be arranged to vary the lost motion of the grippers and thereby to vary the range of movement of each feeding stroke of the paper shifter. A second rod *f* extending between the arms *a* serves as a stay for the arms *a* and also as a stop for the grippers *d'*. At an intermediate point of the shaft *d* is fixed a crank *d*² which is coupled by connecting rod *g* with a crank pin *h'* on a gear disk *h* which is suitably journaled in a fixed part of the apparatus with its axis parallel with the rods *d*, *f*. The teeth of the disk *h* mesh with a pinion *i'* which, for the purpose of silent working, is preferably of compressed fiber or the like, on the armature spindle *i* of a motor having six coils *j* which are coupled in pairs and connected with the bars of a 12-section stationary commutator *k* in the manner shown in Fig. 7. The armature consists of two crossbars of soft iron *l*, and mounted on the armature spindle is a brush *m* rubbing on the commutator bars and connected through a spring contact *m'* with one terminal of the supply. The other terminal from the supply is connected with each of the pairs of poles *j'*, *j'*, *j*², *j*², *j*³, *j*³ and through them with the corresponding sets of commutator bars *k'*, *k*², *k*³, as shown in Fig. 7. As, however, the particular construction of motor forms no part of the present invention and is not essential thereto, it is to be understood that any suitable motor may be employed.

55 The switch arm *c* coöperates with spring contacts *n*, *n'* which are connected respectively with the front stop *o* and back stop *o'* of the writing current relay armature *p*, and are slotted longitudinally to enable the overlap of the switch arm *c* on the contacts *n*, *n'* to be adjusted. As shown diagrammatically in Fig. 6 the motor circuit *q* is normally broken at the relay but is completed as soon as the relay is actuated by a line current. The motor consequently rotates and through the crank *h'* and arms *a* oscillates the rock shaft *b* thereby shifting

the brush *c* from contact *n* to contact *n'*. The motor circuit is thus broken until on the cessation of the line current the armature *p* is brought into contact with the back stop *o'*. This reestablishes the motor circuit and the motor resumes rotation, moving the brush *c* back to the position shown in Fig. 6, thereby again breaking the motor circuit until current is again received from the line.

Having thus described the nature of the said invention and the best means I know of carrying the same into practical effect, I claim:

1. In an apparatus of the class described, the combination of paper shifting means embodying arms, a rotatable electric motor, and a connection between the said arms and the motor for actuating the former, said connection embodying crank mechanism.

2. In an apparatus of the class described, the combination of paper shifting means embodying arms, an electric motor, a crank operatively connected with the paper shifting means for operating the arms, and gear connection between the motor and the crank for operating the latter.

3. In an apparatus of the class described, the combination of a bodily oscillating paper shifter, a rotatable electric motor, and means connecting the motor with the said paper shifter for oscillating the latter.

4. In an apparatus of the class described, the combination of a paper shifter embodying a bodily oscillating support and paper gripping means mounted thereon for movement therewith and independently with respect thereto, a motor, and means connecting the motor with the support and the said gripping means for operating them.

5. In an apparatus of the class described, the combination of a paper shifter embodying a bodily oscillating support and paper gripping means supported thereby for movement therewith and independently with respect thereto, a rotatable motor, and means connecting the motor with the support and the said gripping means for simultaneously operating them.

6. In an apparatus of the class described, the combination of a paper shifter embodying a bodily shiftable support, a gripper member carried by the support and movable with respect thereto, a stop with which the gripper coöperates for gripping the paper, a motor, and means embodying crank mechanism connected with the gripper member and the support, and also with the motor for operating the support and gripper.

7. In an apparatus of the class described, the combination of a paper shifter embodying a shiftable support, a gripper member carried by the support and movable with respect thereto, an adjustable stop with which the gripper coöperates for gripping the paper, a motor, and means embodying

crank mechanism connected with the gripper member and the support, and also with the motor for operating the support and gripper.

5 8. In an apparatus of the class described, the combination of a paper shifter embodying a shiftable support, a gripper member carried by the support and movable with respect thereto, an eccentrically and adjustably mounted stop with which the gripper coöperates for gripping the paper, a motor, and means embodying crank mechanism connected with the gripper member and the support, and also with the motor for operating the support and gripper.

9. In an apparatus of the class described, the combination of a paper shifter embodying a shiftable support, a gripper member carried by the support and movable with respect thereto, a stop with which the gripper coöperates for gripping the paper, a motor, means embodying crank mechanism connected with the gripper member and the support, and also with the motor for operating the support and gripper, and an additional stop for limiting the movement of the gripper member in the opposite direction.

10. In an apparatus of the class described, the combination of a paper shifter embodying a support mounted for oscillating movement, a gripper member carried by the support for movement therewith and for movement independent with respect thereto, a stop with which the gripper member coöperates for gripping the paper, a motor, a crank connected with the motor, and a link connection between the crank and gripper member whereby the operation of the motor will oscillate the said support and operate the gripper member.

11. In an apparatus of the class described, the combination of a paper shifter oscillatable to and fro, a motor, means connecting the motor and paper shifter, a motor circuit including separate conductors, a relay having an armature in the circuit adapted to be connected to one end of either conductor, and a switch carried by and movable with the paper shifter for controlling the motor circuit by making contact with the other end of either conductor.

12. In an apparatus of the class described, the combination of a bodily oscillating paper shifter, a motor, means connecting the motor and paper shifter for moving the latter to and fro, a motor circuit, a relay in the circuit, and a switch connected with and operable by the movement of the paper shifter for controlling the motor circuit through the relay.

13. In an apparatus of the class described, the combination of an oscillating support, a paper gripper carried thereby for movement therewith and for independent movement with respect thereto, a motor, an operative

connection between the motor and the support and paper gripper whereby both will be operated by the motor, a circuit for the motor, and a switch connected with and movable with the support for controlling the motor circuit.

14. In an apparatus of the class described, the combination of a paper shifter movable in opposite directions, a motor operatively connected therewith for operating the former, a motor circuit, a relay included in the motor circuit, said relay being also included in the line circuit, and a switch connected to and operated synchronously with the paper shifter for controlling the motor circuit.

15. In an apparatus of the class described, the combination of an oscillatable paper shifter movable in opposite directions, a motor operatively connected therewith for operating the former, a motor circuit, a relay included in the motor circuit, said relay being also included in the line circuit, and a switch connected to and operated synchronously with the paper shifter, said switch operating to establish a circuit for the motor prior to the deenergization of the relay on the cessation of the line current.

16. In an apparatus of the class described, the combination of a pivotally mounted paper shifter movable in opposite directions, a motor connected therewith for operating the shifter, a circuit for the motor, a relay included in said circuit, said relay including spaced stops and an armature movable therebetween, said relay being also included in a line circuit, and a switch connected to and operated synchronously with the paper shifter for controlling the motor circuit, said switch operating to be positioned to establish the motor circuit through one of the relay stops, when the relay is deenergized by the cessation of the line current, and prior to such deenergization.

17. In an apparatus of the class described, the combination of a non-rotatable paper shifter movable in opposite directions, a motor connected therewith for operating the shifter, a circuit for the motor, a relay included in said circuit, said relay including spaced stops and an armature movable therebetween, said relay being also included in a line circuit, and a switch operated synchronously with the paper shifter for controlling the motor circuit, said switch operating to be positioned to establish the motor circuit through the back stop of the relay when the relay is deenergized by the cessation of the line current, and prior to such deenergization.

18. In an apparatus of the class described, the combination of an oscillatable paper shifter movable in opposite directions, a motor with which the shifter is connected for operation thereby, a circuit for the mo-

tor, a relay included in a line circuit embodying spaced stops relatively adjustable to vary the space therebetween, and a switch synchronously operated with the paper shifter and coöperating with the said stops for controlling the motor circuit.

In testimony whereof I have signed my

name to this specification in the presence of two subscribing witnesses.
